UNITED STATES PATENT OFFICE

2,413,200

DISCONNECTING SWITCH

Joseph S. Thompson, San Francisco, Calif., assignor to Pacific Electric Manufacturing Corporation, San Francisco, Calif., a corporation of California

Application March 15, 1946, Serial No. 654,532

7 Claims. (Cl. 200—169)

1

The present invention relates to electrical circuit disconnecting switches and more particularly to a simple and improved form of locking means for a disconnecting switch of the blade type that will prevent a circuit opening operation of the switch blade by any cause other than through its normal operating means.

The main object of the present invention is to provide a simple and inexpensive locking means of novel construction for disconnecting switches such as are only infrequently operated and used where a switch having a more complicated and expensive locking means could not be economically justified.

Another object of the invention is to provide a novel form of locking means for disconnecting switches of the type having a blade that cooperates with a stationary contact clip in which the blade and contact clip are adapted to become interlocked and disengaged in a new and novel manner.

A further object of the invention is to provide a simple and inexpensive locking means for preventing an accidental circuit opening movement between a switch blade and a stationary contact clip.

Other objects and advantages of the invention will be in part evident to those skilled in the art, and in part pointed out hereinafter in the following description taken in connection with the accompanying drawing, wherein there is shown by way of illustration and not of limitation, a preferred embodiment thereof.

In the drawing:

Figure 1 is a prospective view of a disconnecting switch constructed in accordance with a preferred embodiment of the invention, and

Figure 2 is a vertical sectional view taken along lines II—II of Figure 1, looking in direction of arrows.

For a better understanding of the invention reference is now made to Figure 1 of the accompanying drawing wherein I have shown my improved locking means as applied to a switch of the type such as is employed to disconnect or temporarily isolate a section of high voltage transmission line for the protection of linemen working thereupon or in making repairs or connections. In the drawing the numeral 10 designates a supporting base which, in the present instance, is shown as composed of a length of channel iron upon which vertical insulator stands 11 and 12 of the usual type are mounted in spaced relation. At its upper end the insulator stand 11 is provided with a metallic cap 13 that has an

2

extending terminal lug or boss 14 to which a power line conductor may be connected. This cap 13 also has an upstanding terminal clip 15 upon which a switch blade 16 of rectangular cross section is pivotally mounted by means of a shaft 17. In like manner the insulator stand 12 carries a metallic cap 18 upon which there is formed a terminal lug or boss 14' to which the other conductor of a power line may be connected. Extending upwardly from the top of the metallic cap 18 there are two spaced contact forming members 19 and 20 that form a stationary terminal clip having opposed contact faces between which the free end of the pivotally mounted switch blade 16 is adapted to be positioned when in its closed circuit condition.

As is more clearly shown in Figure 2 of the drawing the contact forming member 19 is provided with an inwardly displaced tongue or boss which forms an abutment 21 that will operate as a stop to prevent an excessive circuit closing movement of the switch blade 16 after it has been positioned between the contact forming members 19 and 20. In like manner the contact member 20 is shown as provided with an inwardly offset portion which forms a locking abutment 22 that will overlie the switch blade 16 and prevent a circuit opening movement thereof after it has been moved into full engagement with the contact faces of the members 19 and 20. At this point it may be mentioned that, in the preferred arrangement, the switch blade 16 will be of such a length and be constructed in such a manner and/or of such material as will permit a twisting thereof without danger of the switch blade taking a permanent set by the required twisting thereof. In addition to this, the invention also contemplates that the upwardly extending contact forming members 19 and 20 will be of such material and construction that they may be spread or flexed outwardly by a twisting of the cooperating end of the switch blade 16 so as to avoid the locking abutment 22 and permit a withdrawal of the switch blade therefrom.

In the present instance, in order to provide a simple and effective means for imparting a combined twisting and circuit opening movement to the switch blade 16, the switch blade is here shown as being bent at a right angle so as to provide a laterally extending arm or lever 23 at one side thereof. This arm or lever 23 may be of any required length and may be adapted for operation by any suitable means. In the present instance this laterally extending arm or lever 23 is shown as provided with two notches 24 and

25 that extend into opposite sides thereof and at different distances from the plane of the switch blade 16. The notch 24 is shown as located nearest to the switch blade 16 and when pressure is applied to the switch blade 16 at this point it may be moved into full engagement with the contact clip formed by the contact members 19 and 20 without any perceptible twisting thereof. By the same token, the notch 25 is located outwardly at a greater distance from the plane of the switch blade 16 so that when a switch blade operating force is applied at this point the free end of the switch blade 16 will be twisted so that its outer edge will be moved out of underlying relation with the stop or locking abutment 22 upon the contact forming member 20 and as a result the switch blade 16 may then be operated freely into its full open circuit position.

It is believed that the operation of my improved switch blade locking arrangement will be fully understood from the above and it therefore appears only necessary to add that the laterally disposed arm or lever 23 may be extended to either side of the switch blade 16. However, if the position of the arm or lever 23 is changed to extend in a reverse direction to that here shown in the drawing it will be evident that the stop forming and blade locking abutments 21 and 22 carried respectively by the contact forming members 19 and 20 will be located on the other of these two members. It will also be understood that, instead of the notches 24 and 25, the laterally extending lever arm 23 may be provided with extending rings or open holes at the positions indicated by these notches for the accommodation of a hook at the end of an operating stick such as is customarily used for the operation of switches of this character. In connection with Figure 2 of the drawing it should be pointed out that the illustrated flexing of the contact clip forming members 19 and 20, and the prominence of the locking abutment 22 have been somewhat exaggerated in order to more clearly illustrate the manner in which the parts cooperate.

While I have, for the sake of clearness and in order to disclose the invention so that the same can be readily understood, described and illustrated a specific form and arrangement, it is to be understood that the invention is not limited to the specific form disclosed, but may be embodied in other forms and arrangements that will suggest themselves to persons skilled in the art. It is believed that this invention is new and it is desired to claim it so that all such changes as come within the scope of the appended claims are to be considered as part of this invention.

Having thus described my invention, what I claim and desire to secure by Letters Patent is:

1. In a disconnecting switch of the character described the combination of a pivotally mounted switch blade having a torsional characteristic adapted to permit a twisting of its free end out of its normal plane, a stationary terminal clip with which the free end of said switch blade is adapted to cooperate to complete a circuit, said stationary clip having opposed contact faces that will spread when the free end of said switch blade is twisted out of its normal plane, means carried by one of said opposed contact faces adapted to retain said switch blade in its circuit closed position, and means for imparting a circuit opening movement to said switch blade adapted to twist the blade and spread the opposed contact faces of said stationary clip and thus render said means

10 inoperative to prevent a normal circuit opening movement of said switch blade.

2. In a disconnecting switch of the character described, the combination of a pivotally mounted switch blade having torsional characteristics adapted to permit a twisting of its free end out of its normal plane, a stationary terminal clip with which the free end of said switch blade is adapted to cooperate to complete a circuit, said stationary clip having opposed contact faces that will spread when the cooperating free end of said switch blade is twisted out of its normal plane, an extending boss carried by one of said opposed contact faces adapted to overlie said switch blade when in its circuit closed position, and means for imparting a circuit opening movement to said switch blade adapted to twist the blade and cause the opposed contact faces of said stationary clip to spread and render said extending boss inoperative to prevent a normal circuit opening movement of said switch blade.

3. In a disconnecting switch of the character described, the combination of a terminal clip forming a pivotal support for a switch blade, a second terminal clip having upstanding clip forming portions providing a stationary contact for the free end of the switch blade, a flexible switch blade pivotally mounted upon said first terminal clip adapted to be moved into a circuit closing position between the upstanding clip forming portions of said second terminal clip, an inwardly extending boss carried by one of the upstanding clip forming portions of said second terminal clip adapted to prevent an inadvertent circuit opening movement of said switch blade when in its circuit closed position, and means at the free end of said switch blade arranged and adapted to flex said switch blade between the upstanding clip forming portions of said second terminal clip to thus render said boss inoperative and prevent a circuit opening movement of said switch blade when a circuit opening force is applied to said means.

4. In a disconnecting switch of the character described, the combination of a terminal clip forming a pivotal support for a switch blade, a second terminal clip having upstanding clip forming portions providing a stationary contact for the free end of the switch blade, a twistable switch blade pivotally mounted upon said first terminal clip adapted to be moved into a circuit closing position between the upstanding clip forming portions of said second terminal clip, an inwardly extending abutment carried by one of the upstanding clip forming portions of said second terminal clip adapted to prevent an inadvertent circuit opening movement of said switch blade when in its circuit closed position, and an operating arm at the free end of said switch blade arranged and adapted to twist said switch blade between the upstanding clip forming portions of said second terminal clip to thus render said abutment inoperative and prevent a circuit opening movement of said switch blade when a circuit opening force is applied to said arm.

5. In a pole type disconnecting switch, the combination of a pivotally mounted switch blade having a length sufficient to permit a twisting of the free end thereof out of its normal plane, a stationary contact with which the free end of said switch blade is adapted to cooperate and complete a circuit, said stationary contact having opposed yielding contact faces between which the end of said switch blade is adapted to be positioned when in its circuit closed position, a

locking abutment upon one of the yielding contact faces of said stationary contact adapted to engage said switch blade when in its circuit closed position between said contact faces, and said switch blade being bent at a right angle at its free end, whereby said switch blade will be twisted out of locking engagement with said abutment when a switch opening force is applied to the right angled end thereof.

6. In a pole type disconnecting switch, the combination of a pivotally mounted switch blade having a length sufficient to permit a twisting of the free end thereof out of its normal plane, a stationary contact with which the free end of said switch blade is adapted to cooperate and complete a circuit, said stationary contact having opposed yielding contact faces between which the end of said switch blade is adapted to be positioned when in its circuit closed position, a locking abutment upon one of the yielding contact faces of said stationary contact adapted to engage said switch blade when in its circuit closed position between said contact faces, and said switch blade being bent at a right angle at its free end and having an operating stick accommodating notch thereupon, whereby said switch blade will be twisted out of locked engagement with said abutment when a switch opening force

is applied to its right angled end by an operating stick.

7. In a pole type disconnecting switch, the combination of a pivotally mounted switch blade having a length sufficient to permit a twisting of the free end thereof out of its normal plane, a stationary contact with which the free end of said switch blade is adapted to cooperate to complete a circuit, said stationary contact having 10 opposed yielding contact faces between which the end of said switch blade is adapted to be positioned when in its circuit closed position, a stop forming abutment upon one of the yielding contact faces of said stationary contact for limiting the circuit closing travel of said switch blade, a locking abutment upon the other said yielding contact faces adapted to overlie the outer edge of said switch blade and lock it in its circuit closed position between said contact faces, said switch 15 blade being bent at its free end to form a right angled extension, and an operating stick accommodating means upon said right angled extension, whereby said switch blade may be moved into its circuit closed position by an operating stick without a twisting thereof and subsequently 20 twisted out of engagement with said locking abutment when a switch opening force is applied thereto through the operating stick.

JOSEPH S. THOMPSON.
